115,582

DESIGN FOR A CIGARETTE BELT

Max Silverman, New York, N. Y.

Application May 27, 1939, Serial No. 85,230

Term of patent 3½ years

To all whom it may concern:

Be it known that I, Max Silverman, a citizen of the United States and a resident of the city of New York, in the county of Kings and State of New York, have invented a new, original, and ornamental Design for a Cigarette Belt, of which the following is a specification, reference being had to the accompanying drawing, forming a part thereof.

Fig. 1 is a fragmentary front elevation of the belt shown in Fig. 3.

Fig. 2 is a fragmentary top plan view of the belt shown in Fig. 3.

Fig. 3 is a perspective view of a cigarette belt showing my new design.

I claim:

The ornamental design for a cigarette belt, substantially as shown.

MAX SILVERMAN.
